UNITED STATES PATENT OFFICE.

THOMAS J. HOGAN, OF PORTLAND, MAINE.

FOLDABLE CUFF OR WRISTBAND.

1,229,614.

Specification of Letters Patent. Patented June 12, 1917.

Application filed September 30, 1916. Serial No. 122,955.

To all whom it may concern:

Be it known that I, THOMAS J. HOGAN, a citizen of the United States, residing at Portland, in the county of Cumberland and State of Maine, have invented certain new and useful Improvements in Foldable Cuffs or Wristbands, of which the following is a specification.

This invention relates to improvements in shirt cuffs or waistbands of the kind which are designed to be ironed soft or unstarched. Cuffs of this character are well-known and popular. As at present made they are adapted to be folded outwardly and back and near the adjacent edges provided with buttonholes which register and through which the cuff button is adapted to pass.

The object of the present invention is to construct the soft cuff or wristband so that its length may be adjusted and so that the exposed or folded edge of the cuff may be changed at will. To accomplish these objects the cuff is provided with a plurality of buttonholes on one side of the folding line and a single buttonhole on the other side. Preferably the plurality of holes are on the inner portion of the cuff. The location of the buttonholes is preferably such that the unused buttonhole will be concealed in all cases.

In the drawings herewith accompanying and making a part of this application Figure 1 is a plan view of a portion of a shirt sleeve and soft cuff constructed according to my invention, the cuff being shown unfolded; Fig. 2 is a plan view showing the cuff folded in one of the positions ready to wear, and Fig. 3 is a similar view showing the cuff folded in another position.

Same reference characters indicate like parts in the several figures.

In said drawings 1 represents a shirt sleeve and 2 a cuff attached thereto. As shown the cuff is provided below the folding lines with a buttonhole 3 and above the folding lines with two or more buttonholes 4 and 5. When two buttonholes are used

in this part of the cuff, the cuff may be folded on the dotted line $x-x$, in which case the cuff button will pass through holes 3 and 5, or it may be folded on the dotted line $y-y$, in which case the cuff button will pass through holes 3 and 4 exposing a different portion of the cuff at the folded edge. The buttonholes should be positioned relative to each other so that when the cuff is folded on either line the free edge of the cuff will overlap and conceal the edge 6 of the sleeve to which the cuff is attached.

It will be understood that applicant does not limit himself to the number of cuff buttonholes nor to the exact location of them, but the form shown seems to be the desirable embodiment of this invention, because in this form the unused buttonhole or buttonholes are concealed as is indicated by the dotted lines in Fig. 2 where the unused buttonhole 4 is under the folded part below the cuff button, and in Fig. 3 where the unused buttonhole 5 is under the folded part above the cuff button.

The advantages of my improved device are many.

The length of the sleeve may be adjusted. The wear time of the cuff may be greatly extended, because the wearing edge can be readily changed. The shirt will not require laundering so often, because the edge of the cuff, which always becomes soiled first, may be readily changed.

Having described my invention and its uses, I claim:

A folding cuff or wristband provided with a plurality of cuff buttonholes above the folding lines and a cuff buttonhole below the folding lines adapted by changing the folding line to register with either button-hole on the other side of the folding line, the holes being spaced apart relative to each other so that when the cuff is folded its free edge will overlap the edge of the sleeve in all cases.

In testimony whereof I affix my signature.

THOMAS J. HOGAN.
